CLAIM

The ornamental design for a covered food storage container or the like, substantially as shown and described.

DESCRIPTION

FIG. 1 is a top perspective view of a covered food storage container or the like showing our new design; FIG. 2 is a side elevational view of FIG. 1, the side opposite being identical thereto; FIG. 3 is a right or left end elevational view thereof; FIG. 4 is a top plan view of FIGS. 1 and 6; FIG. 5 is a bottom plan view of FIGS. 1 and 6; FIG. 6 is a top perspective view of a modification of the covered food storage container of FIG. 1; FIG. 7 is a side elevational view of FIG. 6, the side opposite being identical thereto; and FIG. 8 is a right or left end elevational view of FIG. 6. The stippled shading on the design represents a frosted (opaque or translucent) material.
